UNITED STATES PATENT OFFICE.

LEE P. HYNES, OF ALBANY, NEW YORK, ASSIGNOR TO CONSOLIDATED CAR-HEATING COMPANY, OF ALBANY, NEW YORK, A CORPORATION OF WEST VIRGINIA.

ELECTRIC HEATING SYSTEM.

Application filed October 4, 1921. Serial No. 505,425.

To all whom it may concern:

Be it known that I, LEE P. HYNES, a citizen of the United States, residing at Albany, in the county of Albany and State of New York, have invented certain new and useful Improvements in Electric Heating Systems, the following being a full, clear, and exact disclosure of the one form of my invention which I at present deem preferable.

For a detailed description of the present form of my invention, reference may be had to the following specification and to the accompanying drawings forming a part thereof, wherein—

Fig. 1 is a diagram of my system;

Fig. 2 is a modification;

Fig. 3 shows the application thereto of a switch for changing it from 1200 to 600 20 volts pressure and vice versa.

My heating system is of the type wherein all the heating coils are concentrated in one casing at one point in the car or apartment. Then air is blown into the inlet duct of the 25 casing and over the coils by a fan or other blower and, when heated thereby, is distributed by an outlet duct through the space to be heated. This is known as the blast heating system and has certain notable advantages. Thus by delivering the heated air at the floor line, the floors are warmed and dried as they are not in the ordinary system, of direct radiation by distributed heaters. In addition the circulation and uniform distribution of uniformly heated air is secured, while the air is fresh and is constantly being replenished from the outside. This affords a more sanitary, healthful and comfortable condition. My invention aims to make this 35 highly desirable system more practical than it has proved to be heretofore. A system of this type is illustrated for example in the patent of McElroy No. 1,190,780 of July 11, 1916, also in the patents of Williams No. 40 1,154,587 of Sept. 21, 1915 and Smith No. 1,217,229 of Feb. 27, 1917. My system constitutes an improvement thereon in several respects. In particular it has been attempted in all previous systems I am familiar 45 with to insure the operation of the fan motor when the heaters are on, and this has involved the interlocking either mechanically or electrically of a number of manually operated switches. I have eliminated these

complications and simplify the organization by placing the control of the heaters in the fan motor circuit. By this means I am enabled to also employ a simple and safe type of switch instead of the complicated switches formerly used. I also make all of the respective features as separate units whereby certain ones may be omitted when a less refined organization is desired without interfering with the completeness and workable character of the features which remain. Other advantages of my arrangement will be mentioned hereinafter.

Referring to Fig. 1, A represents a service switch, preferably of the "safety" type, whereby current from the trolley wire TR may be admitted to main heater circuit 1 leading to the group of heater coils 7, 8, 9 and 10, which are arranged within one suitable casing. Through this casing the air to be heated and then distributed is forced by a fan or blower motor F. The switch A is shown diagrammatically as of the snap-break type operated by handle A¹ and provided with blow-out coil A² and main fuse A³. At B is shown an automatic circuit closer which is opened automatically by gravity or a spring and is closed by the magnet 6 in the fan-motor circuit. The switch B is normally open but is closed by the magnet 6 and remains closed only so long as the magnet is energized. Switch B is also shown diagrammatically as of the snap and blow-out type

At E is the heater itself containing four sets of sections of heater coils which are marked respectively 7, 8, 9 and 10. The coils are grouped in a suitable casing into which the cool air is blown by a fan driven by motor F. In the casing at the point where the cool air enters is a small fuse G in the circuit of motor F. That circuit starts from the main circuit to which it is permanently connected at the point 1^a, and, after passing through the resistance H, goes to fuse G, motor F and thence through magnet 6 of switch B to ground. So long as this fan-motor circuit is closed the automatic switch B will be closed and, assuming service switch A to be also closed (switch B can not close unless switch A is closed first) the current will then flow to coils 7 of the heater and to ground. Obviously the main circuit can not be closed

unless this fan-motor circuit is first closed, nor can the heater circuit continue to be energized if the fan-motor circuit is open. The heater coils 7 are to be in circuit whenever, and so long as, the heater is turned on at switch A whereby the fan can not at any time blow cold air through the heater and into the car or apartment.

- At C is a thermostatic switch that acts 10 on the heater-coils 8, 9 and 10 in a group cutting them into circuit whenever the temperature reaches a determined minimum degree and cutting them out at a determined maximum degree. At D is a mercury thermometer which controls switch C. This switch contains a circuit closer 5 operated by coil 11, when energized, to open it and closed by a spring 8 when coil 11 is de-energized—as it will be when short-circuited by the closure of contacts 15 upon the de-energizing of coil 16. The circuit of coil 16 starts from the main circuit at switch 5 and thence passes through magnet 11 (or the contacts 15 which, when closed, short-circuit that magnet) and thence through resistance 13 and coil 16 to the thermostat D where it goes to ground if the thermostat has reached a temperature adequate to close the grounding circuit. Magnet 16 is also 25 shunted by a grounded resistance 14 to eliminate sparking at the thermostat contacts. While the thermostat D is below maximum temperature the switch 15 bridges the contacts which shunt the magnet 11. 30 When the temperature rises so that the circuit is closed by the thermostat the current will pass from main wire 1, through the switch 15, coil 13, magnet 16 and the thermostat to the ground. Thus the magnet 16 is 35 energized and attracts the switch 15, breaking the shunt circuit around the magnet 11, whereupon the last mentioned magnet will be energized, attracting the armature of the switch 5 and breaking the circuit to 40 coils 8, 9 and 10. When the temperature drops the circuit is broken at the thermostat b, and the switches 5 and 15 are returned to their normal positions by their 45 respective springs. 50 Assuming that the service switch A is closed by hand the operation of the system begins and is continued thereafter automatically. The first effect of closing switch A is to apply the trolley voltage to the fan-motor circuit through fuse a^2 , pressure-reducing resistance H, fuse G, fan-motor F, magnet 6 to ground. This will start the fan and likewise close switch B and admit current to heater coils 7. It is thus impossible to admit current to the heater without starting the fan at the same time. Moreover, this arrangement has other valuable qualities. I have found that a large majority of the cases of failure of the fan is 55 included in the following list: (1) a break

or opening in the fan circuit, (2) a defect in the motor such as a broken brush, (3) a blown fuse at a^2 , (4) an open field magnet coil, (5) a break or opening in the fine-wire motor resistance H, (6) a loose connection 70 or a break in coil 6 of automatic switch B. In each one of these cases the result will be to de-energize the coil 6 and allow the switch B to open the main heating circuit. It will also be observed that the coil 6 is 75 located in the fan circuit between motor F and the ground. If it were between the motor F and the trolley, an accidental ground between coil 6 and the motor would cause the motor to stop but leave the coil 6 still energized. Since it is on the ground side of the motor a ground on the circuit at any point will de-energize the coil as well as the motor. The failure of the fan is a critical accident in a blast system, and the danger of it has retarded the adoption of the system in spite of its pre-eminent advantages. If the fan fails there remains no means for moving the air over the heating coils, which (unlike a steam radiator) 80 actually generate a given amount of heat every second and unless this heat is abstracted as fast as generated, it will accumulate even to the extent of setting fire to the car or fusing of the wire of the coils. By cutting off the current from the heating coils in the event of the opening or grounding of the fan circuit the danger is almost wholly removed. There remains, however, 85 the possibility of the fan being mechanically blocked while its circuit remains intact. Since the fan is a comparatively small one, requiring a considerable resistance H in series with it, the accident just mentioned might occur without blowing the small fuse a^2 in the fan circuit. It is for this reason that I include the fuse-link G in series with the magnet 6 in the fan circuit. This fuse-link is located in the heater casing back of 90 the heater coils, this being the point where, in the event of fan failure the dead air would become immediately overheated by the still-active heater coils. Thus the fuse G would be certain to blow in the event of 95 the accident last mentioned, and would not only break the motor circuit but also de-energize magnet 6 and cause the automatic switch B to open the main heater circuit. That will immediately stop the generation of 100 heat and its accumulation at the heater. It should also be remembered that the characteristic of a blast system of heating is the concentration of all the heating coils at one spot, in contrast to the distribution of them 105 throughout the car or compartment in the ordinary system. Thus the entire heating power of the car or compartment becomes concentrated for destruction, in the event of 110 fan failure, as it is concentrated for normal heating under normal conditions. Since no 115

degree of merit in a heating system can compensate for lack of safety, the expedients I have devised have a magnified value in that they help to render the desirable 5 blast system a safe one, making its merits more available.

Fig. 2 shows a means for eliminating the cost of the main switch A shown in Fig. 1 which is a heavy-duty switch and hence a 10 somewhat expensive apparatus, requiring lever mechanism to produce the quick, wide, break, the blowout magnet to extinguish the arc and the safety construction. In place of switch A, I employ merely the main fuse A⁴, or a simple hand service switch, enclosed in a box A⁴. In the far circuit 2 I place two contacts *x* and *y* which are also in box A⁴, and on the door A⁵ of the box I place a contact plate *a*⁵ which will engage *x* and *y* 15 when the door is shut and connect them electrically. Thus the closing of the fuse-box door will close the fan-motor circuit, energizing magnet 6 of switch B and closing thereby the main heater circuit in the way I 20 have described. Since switch B is of the heavy-duty type constructed for safely controlling the main circuit, the switch A becomes unnecessary. I may also place a normally closed switch W in the fan-motor circuit, which, when that circuit is closed at contacts *x* and *y*, may be used to start and stop the heating operation, by closing or opening the fan-motor circuit to energize or de-energize the magnet 6 of switch B. 25 Also, by moving switch W to a second contact *w*², the fan-motor circuit will be closed without the inclusion therein of the magnet 6, a resistance *b*⁶ replacing the resistance of magnet 6 in the circuit. Then the fan-motor 30 will operate without any heating by the coils, serving only as a means of ventilation which is desirable in mild weather when the circulation by means of the hot air would be lacking if it were not for this expedient. 35 The resistance *b*⁶ may be higher or lower than that of magnet 6 to give the fan a greater or less speed when running without the turning on of the heat. As a means of control, the switch W will not be required 40 to break any large current since the fan-motor current is small and hence can be conveniently used to turn the heat on and off. 45 An important advantage of this system is that it is so organized that its separate parts 50 can be used or not as desired. Thus the switch A can be eliminated, as I have described, without disorganizing the remainder of the system. Also if thermostatic control is not desired, as in the cheaper 55 installations, the switch C and thermostat D can simply be omitted and all of the heater coils connected to the main heater circuit 1, or a simple hand-switch can be used for coils 60 7 if their separate control is still desired. 65 For heating interurban cars which are

organized to operate on either 600 volts when in the town, or on 1200 volts when in the country, I provide for shifting the heater from one voltage to the other. This device is illustrated in Fig. 3, wherein there is 70 a change-over switch K under the control of a hand-switch R, the rest of the organization being essentially the same as I have described. The switch K is shown as containing four contact plates *k*¹, *k*², *k*³, *k*⁴ and reciprocating longitudinally, a magnet M¹ acting to draw it to the left (as shown in the drawing) for 1200 volts, with the sets or sections of heater coils connected in series, and a magnet M² acting to draw it to the right 75 for 600 volts, with the sets of heater coils connected in multiple. Switch R serves to send current to magnet M¹ by the wire *r*¹, and to magnet M² by wire *r*². In the series position, shown in the drawing, the heating current from main line 1 goes to coils 7, thence by wire 7^b to plate *k*² and by wire 8^a to coils 8 and thence to ground. A branch circuit from wire 1 goes, by switch 5 on the thermostatic switch C to coils 10, thence by 80 wire 10^b to plate *k*³, and by wire 9^a to coils 9 and ground. Only coils 9 and 10 which are governed by switch 5 are left under control of the thermostat, coils 7 and 8 being 85 constantly connected. When the switch K is moved to the right (Figure 3) by the magnet M², coils 7 will be connected to the ground at point *g* by means of wires 7^b, and the plate *k*⁴ and the coils 8 will receive current from the wire 1, by means of wire 1^a, plate *k*² and wire 8^a. Said coils 8 are grounded as indicated at *g*^a; coils 9 will receive current from wire 1 by thermostatic switch 5, wire 9^a and plate *k*³, being connected to ground at their opposite end. Coils 10 will also receive current from wire 1 by thermostatic switch 5 and are connected to ground by wire 10^b and plate *k*⁴. In this case too, coils 9 and 10 are under thermostatic control. The switch R when in the 90 1200-volt position shown in Fig. 3 will also by means of wire 2^b act to connect the fan-motor circuit to the fan-motor F through the resistance sections H and J, and through 95 one resistance section H, by wire 2^a, in the 600-volt position. It will also, in the 600-volt position, short-circuit, by connecting together wires 30 and 39 through a supplementary contact *r*³, an extra resistance *c*² in the thermostatic switch C, this resistance being only required in the 1200-volt position. Thus by the simple movement of the hand-switch R to right or left, the heater will be 100 organized for either 1200 or 600 volts. In either case a portion of the heater coils will 105 be under control of the thermostat. 110

I am aware that it is not new to utilize the air-pressure, created by the blower when first started, to close the heater circuit by causing such pressure to open a short cir- 115 120 125 130

cuit around a pair of magnets contained in the circuit of the blower motor, the magnets when thus energized by the air pressure serving to operate circuit-closing contacts 5 in the heater circuit. From such an arrangement my claims which require distinction therefrom are distinguished by the statement that the circuit-closer in the heater circuit is controlled directly by the 10 magnet in the circuit of the blower magnet. I also call attention to the single service switch A which acts on heating-coil circuit back of the branch 2 going to the fan-motor circuit, also the fuse A² and contacts x, y 15 and door contact a⁵ which may replace switch A. This is much cheaper than an arrangement of a separate switch for the motor-circuit 2 requiring to be interlocked either electrically with the service switches 20 of the heater coil and also simpler.

What I claim as new and desire to secure by Letters Patent is:

1. An electric heating system comprising heating coils, a casing therefor having an 25 outlet duct leading into the compartment to be heated and an inlet duct supplied with air by a blower, an electric motor for the blower, a circuit-closer for the heating coils and a magnet in the circuit of the motor and 30 in series therewith directly controlling the said circuit-closer.

2. An electric heating system comprising heating coils, a casing therefor having an outlet duct leading to the compartment to 35 be heated and an inlet duct supplied with air by a blower, an electric motor for the blower, a common circuit-closer controlling both the heater and blower-motor circuits in 40 multiple, a second circuit-closer in the heater circuit and a magnet in the blower-motor circuit controlling the said second circuit-closer.

3. An electric heating system comprising 45 heating coils, a casing therefor having an outlet duct leading to the compartment to be heated and an inlet duct supplied with air by a blower, an electric motor for operating said blower, a circuit-closer in the circuit of the heating coils, a magnet in the 50 circuit of said motor controlling said circuit-closer and a heat-responsive device located at the said casing and acting on the circuit of said motor to stop it when the temperature reaches a predetermined maximum.

4. An electric heating system comprising 60 heating coils, a casing therefor having an outlet duct leading to the compartment to be heated and an inlet duct supplied with air by a blower, a motor for said blower, a circuit-closer in the heater circuit, a magnet for operating said circuit-breaker contained in the circuit of said motor between the motor and the ground and a heat-responsive device located at the said casing 65

and acting on the circuit of said motor to stop it when the temperature reaches a predetermined maximum.

5. An electric heating system comprising 70 heating coils, a casing therefor having an outlet duct leading to the compartment to be heated and an inlet duct supplied with air by a blower, a motor for said blower, a circuit branching between the heating coils and the motor, a service switch admitting 75 current to both branch circuits simultaneously, a second switch in the heater circuit, and an operating magnet in the motor circuit for said second switch.

6. An electric heating system comprising 80 heating coils, a casing therefor having an outlet duct leading to the compartment to be heated and an inlet duct supplied with air by a blower, a motor for the blower, a circuit-closer in the heating-coil circuit for 85 admitting current to a set of said coils, and a thermostat subject to the temperature of the compartment to be heated and controlling a portion of the coils controlled by 90 said circuit-closer.

7. An electric heating system comprising 95 heating coils, a casing therefor having an outlet duct leading to the compartment to be heated and an inlet duct supplied with air by a blower, a motor for the blower, a circuit-closer in the heating-coil circuit for admitting current to a set of said coils, a magnet in the motor circuit for operating said circuit-closer and a thermostat subject to the temperature of the compartment to be, 100 heated and controlling a portion of the coils controlled by the said circuit breaker.

8. An electric heating system of the air-blast type comprising heating coils arranged 105 to be put into circuit by closure of the blower-motor circuit, and a single switch which energizes the said motor and thereby also energizes the said coils.

9. An electric heating system of the air-blast type comprising heating coils, a circuit therefor, a blower-motor circuit permanently connected to said coil circuit, a service circuit-closer in said coil circuit outside of the point of said permanent connection, a second circuit-closer in the coil circuit and 115 an operating magnet therefor in the blower-motor circuit.

10. An electric heating system of the air-blast type comprising a heater circuit, a 120 blower-motor circuit, and a switch in said blower-motor circuit containing two contacts and ground connections therefor, one of said ground connections including a magnet operating a circuit-closer in the heater circuit.

11. An electric heating system comprising 125 a plurality of heating-coil sections, a switch for connecting said sections in series or in multiple, a thermostat subject to the temperature of the compartment to be heated, a 130

- relay controlling the heater coils, a thermostat controlling said relay, a resistance in the relay circuit and means for removing said resistance from circuit when the said sections are connected in multiple.
12. An electric heating system comprising heating coils in sections, a switch for connecting said sections in series or in multiple, a thermostat subject to the temperature of the apartment to be heated, and a switch outside of said series-multiple switch controlled by said thermostat whereby the thermostat controls the connection of said sections when in either their series or their multiple relation.
13. An electric heating system comprising four sets of heating-coil sections, a switch for connecting each pair of said sets in series or in multiple and a thermostatic switch subject to the temperature of the compartment to be heated and controlling one pair of said sets in either their series or their multiple relation.
14. An electric heating system comprising a plurality of heating-coil sections, a switch for connecting said sections in series or in multiple, an operating magnet for said switch, a switch controlled by a thermostat which is subject to the temperature of the apartment to be heated, a magnet controlling the connection of said heater-coil sections to the circuit, and controlled by said thermostat, a resistance, and a switch for said operating means provided with means for including said resistance in series with the thermostatically controlled switch when the resistance sections are in multiple.
15. An electric heating system of the air-blast type comprising a plurality of heater-coil sections, a switch for connecting said sections in series or in multiple, a motor-operated blower for directing the air blast over said sections, and means for changing the resistance of the motor circuit as the said sections are in their series or their parallel relation.
16. An electric heating system of the air-blast type comprising heating-coil sections, a service switch therefor, a series-multiple switch therefor and its operating magnet, and supplementary switch contacts for controlling said operating magnet and changing the resistance of the blower-motor circuit.
17. An electric heating system comprising a plurality of heating-coil sections, a series-multiple switch for said sections, an operating magnet for said switch and a service switch for the heater together with supplementary contacts for said operating magnet.
18. An electric heating system comprising a plurality of heating-coil sections, a series-multiple switch therefor, a thermostatic switch controlling said sections, a resistance for said thermostatic switch, a magnet for operating the series-multiple switch and a series switch for the heating coils together with supplementary contacts for controlling said magnet and including the said thermostatic-switch resistance in the circuit or excluding it therefrom.
19. An electric heating system of the air-blast type, comprising a plurality of heating-coil sections, a series-multiple switch therefor, a thermostatic switch and operating magnet therefor and a service switch for the heater together with supplementary contacts for changing the resistance of the blower-motor circuit and the circuit of said operation as the heating-coil sections are changed to their series or their multiple relation.
20. An electric heating system of the air-blast type comprising a plurality of heating coils, a thermostat subject to the temperature of the compartment to be heated and governing the connection of said coils with the circuit, a blower-motor circuit, a switch for connecting the heating coils in circuit and an operating magnet for said switch contained in the said blower-motor circuit.
21. An electric heating system of the air-blast type comprising a plurality of heating coils, a thermostat subject to the temperature of the compartment to be heated and governing the connection of said coils with the circuit, a blower-motor circuit permanently connected in multiple with the heater circuit, a circuit-closer controlling both the heater and the motor circuits and a second circuit closer for the heater circuit operated by a magnet in the motor circuit.
22. An electric heating system of the air-blast type comprising a plurality of heater-coil sections, a series-multiple switch for said sections, a blower-motor circuit, a switch controlling the flow of current to said sections in either their series or multiple relation, an operating magnet for said switch contained in the blower-motor circuit, and a circuit-closer controlling both the heater circuit and the said blower-motor circuit.
23. An electric heating system of the air-blast type comprising a plurality of heater-coil sections, a series-multiple switch therefor, a blower-motor circuit, a switch controlling the flow of current to the heater and a magnet in the blower-motor circuit for operating the said switch.

Signed at Albany, county of Albany and State of New York, this 29th day of September, 1921.

LEE P. HYNES.
